UNITED STATES PATENT OFFICE.

FRANK GOTTFRIED SCHMIDT, OF SAN JOSE, CALIFORNIA.

ORE-SEPARATOR.

1,272,125.

Specification of Letters Patent.

Patented July 9, 1918.

Application filed March 26, 1917. Serial No. 157,477.

To all whom it may concern:

Be it known that I, FRANK GOTTFRIED SCHMIDT, a citizen of the United States, residing at San Jose, in the county of Santa 5 Clara and State of California, have invented new and useful Improvements in Ore-Separators, of which the following is a specification.

This invention has reference to ore separators; and it proposes, briefly, a machine of the general class or character stated, having certain improvements, hereinafter described at length, whereby the gold or other precious metal is readily and effectively 10 separated from the sand and gravel by which it is borne, and discharged from the machine by the aid of comparatively-simple and inexpensive mechanism or devices of special construction.

According to the invention, the improved machine, which is designed primarily to function as an amalgamator, is equipped with a set of agitating devices, preferably in the form of paddles; and these paddles are 15 disposed in two distinct groups, one of which acts to subject the in-coming ore-bearing material to pressure in an upward direction, while the other group subjects it to downward pressure. As a result of this arrangement, the particles of gold or other precious metals are rubbed over the surface of the mercury contained in the cylinder, being cleaned and, to some extent at least, polished thereby during such action, and 20 combine or amalgamate with the mercury in the usual way; whereas the sand, gravel and the like are forced upward through the cylinder and discharged therefrom by way of an outlet trough or chute. The ore-bearing material is fed into the cylinder through a special trough or chute, which delivers it at the level of the mercury, so as to be acted upon by the latter and the separating paddles; the passage of said material through 25 the feed chute and the cleaning of the values being facilitated by means of water jets. Other improvements and advantages will appear as the description proceeds.

In the accompanying drawing:

50 Figure 1 is a vertical sectional view of an ore separator embodying the invention.

Fig. 2 is a plan view thereof.

Fig. 3 is a transverse section on line 3—3,

Fig. 1.

55 Referring more particularly to said drawing, 5 indicates, generally, the cylinder ele-

ment of the machine, the conical bottom 6 of which constitutes a mercury tank of container and is provided at its apex with an opening into which leads the up-turned end 60 of a discharge pipe 7, the latter being equipped with a suitable controlling valve 8. The cylinder may have any desired size, and may be constructed of any suitable material, and it is preferably furnished at the junction of its bottom and body portions with a set of apertured feet 9, by means of which it may be fastened to a frame or support, (not shown).

At its top and bottom, the cylinder body 70 is provided with cross-pieces 10 and 11, having alining bearings 12 and 13 for the upper and lower portions of a vertical shaft 14, the upper end of the shaft also passing through an opening in a second cross-piece 75 15 disposed above and parallel with the cross-piece 10, the depending legs 16 at the opposite ends of the second cross-piece 15 being fixed to the cylinder 5. This shaft 14 carries the two groups of agitating devices 80 previously referred to, said devices being in the form of sheet metal paddles or blades 17 and 18. These paddles or blades are arranged in sets of four, fixed to collars 19, adjustably secured to said shaft, and they 85 may have any desired conformation, but preferably are sector-shaped, as shown, their side or radial edges being curved in one direction or the other, according as they are to exert either a lifting or a lowering pressure upon the material under treatment. In 90 the present embodiment, the lifting group comprises the three upper sets of paddles 17, which, therefore, have their leading radial edges depressed and their rear radial edges 95 elevated, as shown, while the lowering, separating or rubbing group comprises the fourth or bottom set of blades 18, the edges of which are, of course, bent reversely to those of the lifting blades; the said blades 18 100 having their up-bent leading edges slit transversely, and the portions 20 between the slots bent backward to provide spaces through which the sand and gravel may 105 ascend after having been acted upon by the mercury. The four sets of paddles are equidistantly spaced, and the lowermost set 18 is located just above the surface of the mercury, in position to act upon the in-coming ore-bearing material and rub it over 110 the mercury in the manner subsequently explained, the paddles of the succeeding sets

having different angular dispositions relative to one another, as shown in Fig. 1.

The paddle shaft 14 may be driven in any suitable way, but at a comparatively slow speed, so as to prevent the in-coming material from being immediately carried upward by centrifugal force and discharged from the cylinder before separation is effected. According to the construction illustrated, 10 the said shaft is provided with a large worm gear 21, which is disposed between the two upper cross-pieces 15 and 10, and is in driving engagement with a worm 22, the latter being mounted on a horizontal shaft 23 15 whose opposite ends are journaled and supported in bearing openings provided at the ends of a pair of horizontal arms 24 that are rigidly connected to the legs 16 of the upper cross-piece 15. The worm shaft 23 20 may, in turn, be driven from any desired source of power.

The material to be treated is supplied to the cylinder through a trough or chute 25, which is disposed against one side of said cylinder and extends from top to bottom of the cylinder body, its lower end opening at 30 into the cylinder approximately in line with the rubbing blade 18. The chute is of constant breadth, but of gradually-decreasing width from its upper to its lower end, and since it is co-extensive in height with the cylinder, a continuous gravitational feed of the material into the cylinder will be insured, this feeding action being facilitated 35 by means of a spray of water, the spraying pipe 26 passing horizontally through the chute approximately midway between the ends of the latter.

Additional water pipes 27, 27, opening 40 into the lower portion of the cylinder, are also provided for the purpose of assisting the gravitational settling of the heavy metal particles toward the cylinder bottom, and the cleaning of said particles, as well as the 45 ascent of the sand and gravel after the metal particles have been separated therefrom.

The discharge of the afore-mentioned sand and gravel is effected by way of an inclined outlet chute 28, located at the upper portion 50 of the cylinder and fastened to the wall thereof in any desired way, the chute being located in a plane below that of the upper edge of the feed chute and opening into the cylinder at its upper or inlet end, so that 55 the sand and gravel will pass thereinto, under the action of the topmost set of paddles 17, on reaching the top of the cylinder. Provision is made for catching any metal particles which may be carried upward by the lifting paddles, this being effected by equipping the outlet chute with 60 riffles 29, between which the metal particles will settle in passing along the said chute.

In operation, the ore-bearing sand, gravel, 65 etc., are fed into the supply or inlet trough

25, and pass therethrough by gravity, assisted by the jets of water from the spraying pipe 26, into the cylinder through the opening 30 at the bottom of the chute, said opening being located just above the level of the 70 mercury (indicated by the broken line 66, Fig. 1) in the conical bottom of the cylinder and in line with the lowermost paddles 18, as previously stated, and being of such a shape as to deliver the material in a comparatively thin layer. The paddle shaft 14 having been previously set in motion, its paddles 18 will immediately engage the material and spread it over the surface of the mercury, against which the metal particles will be vigorously rubbed.

This rubbing action will tend to separate the metal particles from the sand and gravel and, to some extent at least, polish them; and at the same time, said particles 85 will be subjected to a washing action by the water issuing from the two pipes 27, the particles finally combining with the mercury in the usual way and settling down toward the bottom of the mercury container 6, whence 90 they may be removed by drawing off the mercury through the pipe 7. As the material continues to be fed into the cylinder through the chute 25, the actions above described likewise continue, and the sand and 95 gravel, after the metal particles have been separated therefrom, rise through the spaces formed by the downward bending of the tongues 20 until they come within reach of the lowermost set of lifting paddles 17. 100 The latter raise the waste material to the next higher set of paddles, and they, in turn, lift it still higher into position to be acted upon by the topmost set, the material finally being expelled from the cylinder by way of 105 the discharge chute 28, the riffles 29 with which said chute is furnished serving to catch any metal particles which may possibly have escaped separation from the waste during the rubbing action effected by the 110 lowermost paddles 18. The rotation of the various sets of paddles serves to keep the entire body of material continuously in motion as will be understood, thus avoiding clogging, while the streams of water introduced 115 into the cylinder through the two pipes 27 assist both the upward travel of the waste material and the gravitational settling of the metal particles, as well as serving, to some extent, to wash and thereby clean said particles. Should it be found necessary to 120 empty the cylinder at any time, this may be readily effected, due to the provision of a door 31 through which the contents of the cylinder may be removed, said door being 125 here shown as located in the lower portion of the cylinder at the opposite side thereof from the supply chute 25.

While the apparatus is designed primarily for separating the metal particles 130

by amalgamation, it is to be understood that such method need not necessarily be followed, since the apparatus may be operated without the use of mercury, as the 5 metal particles, being heavier than the sand and gravel, will settle down by gravity to the bottom of the cylinder, whence they may be withdrawn through the pipe 7. It is also to be understood that in any case no 10 limitation to the precise structural details disclosed is contemplated, as the invention is obviously susceptible of modification within its specified scope as claimed.

I claim as my invention—

15 1. In an ore separator, the combination of a cylinder; a vertical shaft mounted therein; driving means for said shaft; and upper and lower groups of agitating paddles carried by said shaft; the lower group 20 of paddles being arranged to exert a downward rubbing pressure upon the material under treatment so as to separate the metal particles from the waste and force said particles toward the bottom of the cylinder, and 25 the upper group of paddles being arranged to exert an upward pressure against the waste so as to cause the same to ascend through said cylinder; said lower group of paddles having portions of their leading edges recessed laterally to provide inwardly extending spaces through which the waste may pass into the sphere of action 30 of the upper group.

2. In an ore separator, the combination 35 of a cylinder having a depending bottom portion provided with a discharge opening; a rotary vertical shaft mounted in said cylinder; upper and lower sets of agitating paddles secured to said shaft; and means 40 for introducing the ore-bearing material in a comparatively thin, horizontal layer into said cylinder at a point substantially in line with the lower group of paddles; the said lower group of paddles being inclined in a 45 direction to exert a positive rubbing action directly upon the surface of the material under treatment so as to separate the metal particles from the waste and force said par-

ticles downward toward the bottom of the cylinder, while at the same time lifting 50 the waste into the sphere of action of the upper group, and the upper group of paddles being inclined in a direction to exert an upward pressure against the waste so delivered thereto so as to cause the waste to ascend through said cylinder; said metal particles settling down in said bottom portion to be withdrawn therefrom through said discharge opening.

3. In an ore separator, the combination 60 of a cylinder having a depending bottom portion provided with a discharge opening; a rotary vertical shaft mounted in said cylinder; upper and lower sets of agitating paddles secured to said shaft; and a vertical 65 chute for the ore-bearing material to be treated arranged at one side of the cylinder and opening at its lower end into said cylinder at a point substantially in line with the lower group of paddles, so as to effect 70 a continuous gravitational feed of said material in a comparatively thin, horizontal layer in position to be directly acted upon by said lower group; the said lower group of paddles being inclined in a direction to exert a 75 positive rubbing action directly upon the surface of the material under treatment so as to separate the metal particles from the waste and force said particles downward toward the bottom of the cylinder, while at the same 80 time lifting the waste into the sphere of action of the upper group, and the upper group of paddles being inclined in a direction to exert an upward pressure against the waste so delivered thereto so as to cause 85 the waste to ascend through said cylinder; said metal particles settling down in said bottom portion to be withdrawn therefrom through said discharge opening.

In testimony whereof I have hereunto set 90 my hand in presence of two subscribing witnesses.

FRANK GOTTFRIED SCHMIDT.
